UNITED STATES PATENT OFFICE.

WILLIAM H. BRISTOL, OF WATERBURY, CONNECTICUT, ASSIGNOR TO THE BRISTOL COMPANY, OF WATERBURY, CONNECTICUT, A CORPORATION OF CONNECTICUT.

SYNCHRONIZED ENTERTAINMENT APPARATUS.

1,396,401.

Specification of Letters Patent.

Patented Nov. 8, 1921.

Application filed July 25, 1919. Serial No. 313,263.

To all whom it may concern:

Be it known that I, WILLIAM H. BRISTOL, a citizen of the United States, and a resident of Waterbury, in the county of New Haven and State of Connecticut, have invented certain new and useful Improvements in Synchronized Entertainment Apparatus, of which the following is a specification.

The invention relates to the operation of automatically synchronized apparatus, more particularly to the synchronous operation of a plurality of entertainment mechanisms, such as motion picture taking and projecting apparatus, sound reproducing machines, piano-players, musical instruments and the like. In a prior Patent, No. 1,234,127, granted to me the 24th day of July, 1917, I have disclosed apparatus whereby the synchronization of such apparatus may be effected in a most satisfactory manner; and in a further Patent, No. 1,234,170, granted July 24th, 1917 to Manfred J. Johnson, further means are disclosed whereby the apparatus may be conveniently and accurately re-synchronized should the respective members for any reason get out of step.

In the operation of the system disclosed in the aforesaid patents, one of the various members to be synchronized is positively driven and its rotation is communicated through the medium of synchronized transmitting and receiving members to one or more further entertainment mechanisms which it is intended shall operate in synchronization with the positively driven mechanism. In certain instances, it has been found that to obtain a very fine regulation or governing of one of the entertainment mechanisms, as the talking machine, it is more satisfactory to provide positive driving means for each of the various mechanisms rather than to transmit the rotation of a single positively driven mechanism to the other or others.

For example, in the making of piano records by perforating a paper strip synchronously with the production of a phonographic record, it has been found that if the apparatus for perforating the former be driven from the apparatus cutting the latter, the phonographic apparatus is not likely to function satisfactorily, in that its governing mechanism does not operate with sufficient precision due to the considerable variation of power required by the piano record-mak-

ing apparatus under the changing effort resulting from the varying number of keys placed in action. In accordance with the present invention, this variable load on the one apparatus does not react on the other, for example a talking machine; and it is possible to successfully make a plurality of records of different character simultaneously, that is to say a phonographic record may be secured synchronously with a piano or organ record and a motion picture film, each being effected under the proper conditions of speed requisite for the particular device. In starting and stopping, moreover, a minimum of inertia only need be overcome and shock is obviated.

The present invention, therefore, has for its object to provide means which will enable the various entertainment mechanisms to be individually driven and still positively be maintained in synchronization with each other; that is to say, while one mechanism may require only a slight driving power and be susceptible to close regulation as by a sensitive governing device, for example in the case of a talking machine, another may be driven with considerable power, for example as a motion picture machine, the same having its speed accurately controlled by the governing device of the aforesaid mechanism. In this manner, while absolute synchronization is maintained, each device is provided with the requisite driving power and the velocity of rotation of all accurately governed. The arrangement, moreover, is such that, especially for the mechanism requiring the greater power, substantially full torque is available at all speeds and no sudden starting effort is met with resulting, frequently, in case of a motion picture apparatus, in tearing of the film.

The nature of the invention, however, will be best understood when described in connection with the accompanying drawings, in which—

Figure 1 illustrates, diagrammatically, the general arrangement of the apparatus.

Fig. 2 is a detail view of the talking machine portion of the apparatus; and Fig. 3 is a similar view of the motion picture portion of the apparatus.

Similar characters of reference designate corresponding parts throughout the several views.

Referring to the drawings, the general lay-

100

110

out of the system is shown more particularly in Fig. 1 of the drawings, wherein the apparatus is shown more or less diagrammatically and the electrical connections 5 between same indicated. Although for the sake of simplicity but two mechanisms—a phonographic device and a motion picture apparatus—are shown interconnected, yet it is to be understood that the invention is 10 not restricted to such combination, but contemplates the simultaneous operation of two or more entertainment devices, as more especially set forth in my aforesaid prior U. S. Letters Patent No. 1,234,127. In the arrangement shown in the drawings herewith, 15 10 designates a talking machine of any well-known construction provided with a governing device 11 which may be of well-known or special construction and is designed to 20 maintain constant the rotation of the turn-table 12 of said talking machine and in conformity with the particular pitch required. The turn-table 12 may be driven in any convenient manner, and as shown more particularly in Fig. 2 of the drawings, is driven 25 from a motor 13 through the medium of a belt 14. The spindle 15 of the turn-table is extended and connected to the rotor shaft 16 of a transmitter member 17 of synchronizing apparatus, such as set forth in the 30 said U. S. Letters Patent No. 1,234,127, communicating to the said transmitter member the velocity of rotation of the spindle 15 or a multiple thereof. The transmitter 35 member 17 is constructed similarly to the transmitter member disclosed in the aforesaid Letters Patent Nos. 1,234,127 and 1,234,170, and consists in general of a rotatable element or rotor and a coacting member or stator, the windings of the same being in inductive relationship to each other as primary and secondary. The transmitter member 17 is connected to a similarly constructed receiver or driven member 17', two 40 45 leads 18 connecting the rotor portions in series and deriving energy from a suitable source of alternating current as the generator 19, while the stator members are interconnected by means of three leads 20, as 50 more particularly set forth in the aforesaid Letters Patent. In this manner, any movement 55 of the rotor of the transmitter or driving member is simultaneously duplicated in the rotor of the receiver or driven member through the production of equalizing currents in the receiver member when the two 60 rotatable members do not occupy corresponding positions relatively to their stator members. If desired, the stator member 21 of 65 the transmitter 17 may also be arranged to be rotated as through a hand wheel 22 and bevel gears 23 to advance or retard the receiver with reference to the transmitter, as more particularly set forth in the aforesaid 65 U. S. Letters Patent No. 1,234,170.

Another entertainment mechanism or a plurality of entertainment mechanisms may be synchronously operated with the talking machine 10, for example a motion picture apparatus 30, as illustrated. This device is 70 not driven, as heretofore, by the power derived from the receiver member, communicated thereto by the transmitter member, but through a separate and distinct source, as for example a motor 31 which can thus 75 be made of the desired capacity to provide ample starting torque. There is provided, however, in accordance with the present invention, between said motor and the entertainment device as the motion picture machine 30 indicated, a speed gear 32 of suitable construction, and preferably a fluid gear such as of the type disclosed in U. S. Letters Patent No. 1,220,424 granted March 27th, 1917 to Reynold Janney, the said speed 80 gear being connected through coupling 33 with the motor 31, and through suitable gears and sprocket chain 34 to the shaft 35 for operating the motion picture machine 30 at the required speed. 90

The speed gear 32 is so designed that the full power is delivered by same from the motor 31 to the shaft 35 of the motion picture machine, yet the velocity of rotation is controlled absolutely by the rotation given to a further shaft 36, herein shown as extending at right angles to the power shaft 35. This shaft 36 may be rotated in any suitable manner as set forth in the said Letters Patent No. 1,220,424, but in accordance 100 with the present invention is controlled by the rotation of the receiver or driven member to the rotor of which it is suitably connected to partake of the rotation thereof. In this manner, any movement of the transmitter rotor effects a corresponding movement of the shaft 35 of the motion picture machine 30, which latter will, therefore, faithfully follow the rotation of the talking machine turn-table 12 whose speed is 110 governed with precision by the governing device 11. It will be appreciated, moreover, that the latter is not reacted upon by the power affecting the motion picture or other mechanism, but has merely to govern the 115 velocity of rotation of the turn-table 12 and the connected rotor of the transmitter device 17. The rotation of the latter is then communicated to the receiver or driven member, which in turn absolutely controls the 120 velocity of rotation of the talking machine as set forth.

I claim:

1. Synchronized entertainment apparatus embodying rotatable entertainment mechanism, means to rotate same and governing means to maintain a constant rotational velocity thereof, additional entertainment mechanism, and independent driving means, connections between said additional enter- 125 130

ainment mechanism and independent driving means, said connections including a speed gear, and speed regulating mechanism operatively associated with said speed gear and controlled by said governing means.

2. Synchronized motion picture and talking machine apparatus embodying a rotatable talking machine, means to rotate same and governing means to maintain constant rotational velocity thereof, a motion picture machine, an independent driving means, connections between said motion picture machine and independent driving means, said connections including a speed gear, and speed regulating mechanism operatively associated with said speed gear and controlled by the governing means of the talking machine.

20 3. Synchronized motion picture and talking machine apparatus embodying a rotatable talking machine, means to rotate same and governing means to maintain constant rotational velocity thereof, a motion picture machine, an independent driving means, connections between said motion picture machine and independent driving means, said connections including a speed gear, and speed regulating mechanism operatively associated with said speed gear, synchronized with the talking machine and controlled by the governing means thereof.

35 4. Synchronized motion picture and talking machine apparatus embodying a rotatable talking machine, means of relatively small power to rotate same and governing means to maintain constant rotational velocity thereof, a motion picture machine, an independent driving means of relatively large power, connections between said motion picture machine and independent driving means, said connections including a speed gear, and speed regulating mechanism operatively associated with said speed gear and controlled by the governing means of the talking machine.

50 5. Synchronized entertainment apparatus embodying a rotatable entertainment mechanism; means to rotate same and governing means to maintain a constant rotational velocity thereof, additional entertainment mechanism, an independent driving means,

connections between said additional entertainment mechanism and independent driving means, said connections including a speed gear, and speed regulating mechanism, comprising a rotatable receiver device including a stator member and a rotor member, the rotor member thereof being connected to the said speed gear, and a transmitter device including a stator member and a rotor member, the latter being connected to the rotatable element of the first-named entertainment device, one of each of the transmitter and receiver devices of the regulating mechanism constituting an electrical field and the other an armature, a source of alternating current, and electrical connections between said source and each of said transmitter and receiver devices, whereby equalizing currents are produced therein when the corresponding rotor members do not occupy corresponding positions relatively to their stator members.

60 6. Synchronized entertainment apparatus embodying a rotatable entertainment mechanism: means to rotate same and governing means to maintain a constant rotational velocity thereof, additional entertainment mechanism, an independent driving means, connections between said additional entertainment mechanism and independent driving means, said connections including a speed gear, and speed regulating mechanism comprising a rotatable receiver device connected to the said speed gear, and a transmitter device connected to the rotatable element of the first-named entertainment mechanism, the said receiver and transmitter devices each having a primary and secondary winding, one of which is provided with a rotatable element, and a source of alternating current, the one set of windings being connected thereto and the other interconnected for the purposes of producing equalizing currents therein when the rotatable elements do not occupy corresponding positions relatively to their coacting members.

Signed at New York, in the county of New York and State of New York, this 23rd day of July, A. D. 1919.

WILLIAM H. BRISTOL.
